CLAIM

The ornamental design for a camera pedestal, as shown and described.

DESCRIPTION

FIG. 1 is a top and front perspective view of a camera pedestal showing my new design;

FIG. 2 is a top and back perspective view thereof;

FIG. 3 is a front view thereof;

FIG. 4 is a back view thereof;

FIG. 5 is a first side view thereof;

FIG. 6 is a second side view thereof;

FIG. 7 is a top view thereof;

FIG. 8 is a bottom view thereof;

FIG. 9 is a top and front perspective view thereof with the camera pedestal coupled to a camera; and,

FIG. 10 is a top and back perspective view thereof with the camera pedestal coupled to a camera.

The broken lines shown in the drawings represent portions of the camera pedestal and form no part of the claimed design. The additional broken lines depicting a camera portion in FIG. 9 and FIG. 10 are for the purpose of disclosing the environment and form no part of the claimed design.
